UNITED STATES PATENT OFFICE.

JAMES W. SEE, OF HAMILTON, OHIO.

SYSTEM OF TUNNELING.

No. 804,437.

Specification of Letters Patent.

Patented Nov. 14, 1905.

Application filed June 30, 1905. Serial No. 267,727.

To all whom it may concern:

Be it known that I, JAMES W. SEE, a citizen of the United States, residing at Hamilton, Butler county, Ohio, (post - office address 5 Opera House, Hamilton, Ohio,) have invented certain new and useful Improvements in Systems of Tunneling, of which the following is a specification.

This invention pertains to an improved system of tunneling adapted for subway construction in cities and will be readily understood from the following description, taken in connection with the accompanying drawings, in which—

15 Figure 1 is a vertical transverse section of a system of tunneling exemplifying my invention; and Fig. 2, a plan, part horizontal section, of the same upon a reduced scale.

In the drawings, 1 indicates the pavement 20 of a city street; 2, the sidewalk; 3, the main tunnel in process of construction; 4, its roof; 5, its side walls; 6, the crown of the main tunnel, comprising the entire roof portion between the tunnel-roof proper and the street- 25 pavement; 7, a subtunnel disposed below the main tunnel; 8, a track in the subtunnel; 9, a branch from the subtunnel; 10, an upcut from the branch subtunnel to the main tunnel; 11, an elevator in the upcut; 12, a housing over the upcut; 13, a track in the subtunnel branch 9 leading from track 8 to the upcut; 14, a construction-car; 15, a track in the main tunnel leading from the upcut; 16, a track in the main tunnel leading from the 35 neighborhood of the upcut to the heading of the main tunnel; 17, a turn-table at the junction of tracks 15 and 16; 18, a heading of the main tunnel; 19, intermediate columns in the main tunnel, and 20 an alternative line for the 40 branch tunnel leading from the subtunnel to the upcut.

In carrying out this system of tunneling the subtunnel, with its track, is first constructed and equipped complete. It should lead to the 45 spoil heap. The branch tunnel 9 is then to be driven, after which the upcut is carried up to a point sufficiently high above the intended floor-level of the main tunnel, the branch and the upcut being lined complete and equipped 50 for service as a lateral and vertical branch of the subtunnel, the housing 12 serving to guard the upcut. A drift from the upcut is then to be driven with its floor at the level of the intended floor of the main tunnel, this drift being transverse to the line of the main tunnel. 55 The spoil from this transverse tunnel is to be

disposed of through the subtunnel. The drift is to be carried full height of the main tunnel and either completed or temporarily lined, the former being preferable. The completed 6c drift should extend the full width of the main tunnel, and when done it represents a short section of the complete main tunnel, and it presents two headings from which the driving of the main tunnel may be carried on, 65 track 16 being extended as the work at the heading progresses. Having served its purpose, housing 12 may be removed when the main tunnel is completed over the upcut. There may be additional branches and upcuts 70 from the subtunnel to permit the main tunnel to be worked from quite a number of headings at once. The sizes of the branch subtunnel and the upcut should be such as to permit the proper passage outward of the spoil and the 75 proper passage inward of the material of construction for the main tunnel. The branch subtunnel may be at right angles to the subtunnel, as at 9, or it may be a switch branch, 80 as at 20. In the construction of the main tunnel the crown material of the street, together with all of its contained pipes, conduits, &c., should be properly supported temporarily until the tunnel-roof is constructed and provided with the overhead ramming to transfer the 85 load of the street to the structural work of the tunnel. A preferable construction for the main tunnel comprises wall-beams, roof-beams, walls, and roof-arches, and with this form it is preferred that each panel of the 90 main tunnel be completed in succession from the point of beginning at the upcut to points as close to the headings as is expedient. If the main tunneling should encounter pipes, 95 sewers, or the like, which it must displace, substitutes for them may be built at the sides of the main tunnel or below, as indicated at 21.

It will be noted that the completed system involves the presence and cost of two tunnels instead of one, or, in other words, a subtunnel in addition to the main tunnel. This might at first thought appear to be an engineering absurdity; but under the conditions contemplated by the system a proper analysis causes the absurdity to disappear. Under 105 ordinary circumstances a subway with a comparatively thin crown requires to be constructed by the cut-and-cover system, and this involves dealing with all of the pipes, conduits, &c., finding their home immediately below the street-surface, and many of these matters must be so dealt with as to

avoid the interruption of their service, calling often for a substitute construction, then a removal of the original construction, and then a replacing of it. Furthermore, the interruption to traffic, if permitted, is a serious annoyance, and if not permitted then the work requires to be done in non-traffic periods under very expensive conditions. All of these matters taken together, as incident to the construction of the subway, may exceed in cost that of a subway proper if it could be driven from headings. In other words, the incidental expense may exceed the main expense.

By the compound system herein provided for the traffic upon the street is entirely undisturbed, and the work may be rapidly pushed day and night by working from any desired number of headings in the main tunnel at one time. Furthermore, the subtunnel may upon the completion of the main tun-

nel continue to serve useful purposes for the passage of material whose transportation through the main tunnel is not desired. For instance, the main tunnel may be devoted to passenger transportation and the subtunnel may be devoted to freightage.

I claim as my invention—

The improved method of tunneling consisting in constructing a subtunnel below and continuous to the proposed main tunnel; constructing a branch from the subtunnel; constructing an upcut leading from said branch to a point in or contiguous to the line of the proposed main tunnel; and constructing the main tunnel by the aid of said upcut, said branch, and said subtunnel.
